UNITED STATES PATENT OFFICE.

HERMAN H. CLAUSSEN, OF SAN ANTONIO, TEXAS.

LOCK UNIT.

Application filed May 13, 1924. Serial No. 713,058.

To all whom it may concern:

Be it known that I, HERMAN H. CLAUSSEN, a citizen of the United States, residing at San Antonio, in the county of Bexar and State of Texas, have invented certain new and useful Improvements in Lock Units, of which the following is a specification.

This invention relates to improvements in locks and more particularly to a lock unit adaptable to ordinary door locks, although it may find embodiment in a unitary structure.

The ordinary door lock comprises a latch mechanism with which the usual spindle and knobs are associated and through the manipulation of which the door may be latched and unlatched, and, in addition thereto, a lock mechanism which is actuated through the medium of a key. This type of lock has been in use many years and various makes or models thereof are quite expensive due to the necessity of providing both a latching and a locking means in a unitary structure. Not only are the lock mechanisms of such locks expensive, but they are also open to the objection that they may be forced and the doors to which they are applied thus opened, surreptitiously. Furthermore, when such locks are so constructed that the knobs upon the ordinary spindle are fixed or held against rotation when the lock is in locked position, it is possible to force the lock by the application of rotative force to the knobs or spindle. In view of the foregoing, it is one of the important objects of the present invention to provide a lock unit which may be quickly and readily installed in connection with any ordinary lock now in use and which will avoid the necessity of employing a locking mechanism separate and distinct from the latch mechanism, as is now the custom. Likewise, the invention contemplates, in this connection, the provision of a lock unit which, when installed, cannot be manipulated so as to force the lock and permit retraction of the bolt of the locking mechanism.

Another object of the invention is to provide a lock unit, applicable to any ordinary

lock or latch such as is employed upon doors, which unit will embody a handle member in the form of a knob housing the locking means which, through the use of a key, may be so adjusted as to permit of rotation of the lock spindle to retract the lock or latch bolt, may be adjusted to permit of use of the lock through the usual manipulation of the knob, and which also be adjusted to free the knob so that it will rotate freely independently of the spindle, thus preventing forcing of the lock through rotation of the spindle by application of rotative force to the knob.

Another object of the invention, and an important one, is to provide a lock unit which may be placed upon the market at a low cost and which may be readily installed by the purchaser thereof, in connection with any ordinary lock of standard type, the lock unit of the present invention being designed to take the place of the ordinary spindle and knobs which are associated with the latch mechanism of such a lock and serve as a highly efficient and more protective substitute for the lock mechanism already present in such a standard lock.

The lock embodying the present invention is designed more particularly for use in office buildings, hospitals, houses, public buildings, and the like, where it is desirable to provide for free entrance and exit from the room closed by the door to which the lock is applied, to likewise permit of secure locking of the said door, and, furthermore, to permit of locking of the door in a manner to positively preclude opening thereof.

Another object of the invention is to provide a lock unit which may be adapted to locks which are already installed and associated with such locks regardless of the thickness of the door or the mechanism of the lock to which the unit is adapted, and which unit will enable the purchaser to obtain all of the advantages of the original lock and the other advantages outlined above.

In the accompanying drawings:

Figure 1 is a view partly in side elevation and partly in section illustrating the application of the lock unit of the present in-

vention to an ordinary combined lock and latch already installed upon the door.

Figure 2 is a view in front elevation of the face plate of the unit, the knobs and 5 spindle of the unit being removed and the parts being shown in section.

Figure 3 is a vertical longitudinal sectional view in detail through the unit embodying the invention, the component parts 10 of the lock mechanism being shown in the position which they will occupy when the mechanism is in locking condition.

Figure 4 is a horizontal sectional view on the line 4—4 of Figure 3, looking in the 15 direction indicated by the arrows and illustrating the mechanism in the same position as shown in Figure 3.

Figure 5 is a view similar to Figure 3, illustrating the component parts of the lock 20 mechanism in the position which they will occupy when a proper key is inserted into the barrel of the mechanism for the purpose of actuating the mechanism to retract the bolt of the lock and thus unlock the door.

25 Figure 6 is a horizontal sectional view on the line 6—6 of Figure 5, looking in the direction indicated by the arrows, the mechanism being in the condition shown in Figure 5.

30 Figure 7 is a view similar to Figures 3 and 5 and illustrating the component parts of the mechanism in the position which they will occupy when the mechanism is adjusted for use during daylight or business 35 hours and under which conditions the knob is rotatable to actuate and retract the bolt of the lock in the same manner in which the knob of an ordinary lock may be turned to actuate the latch bolt thereon.

40 Figure 8 is a horizontal sectional view on the line 8—8 of Figure 7, looking in the direction indicated by the arrows and illustrating the mechanism in the condition shown in Figure 7.

45 Figure 9 is a vertical transverse sectional view taken on the line 9—9 of Figure 3 looking in the direction indicated by the arrows.

50 Figure 10 is a similar view taken on the line 10—10 of Figure 3, looking in the direction indicated by the arrows.

Figure 11 is a vertical transverse sectional view on the line 11—11 of Figure 3, looking in the direction indicated by the arrows.

55 Figure 12 is a diametric sectional view in detail on the line 12—12 of Figure 11, looking in the direction indicated by the arrows.

60 In Figure 1 of the drawings, there is illustrated, in a more or less general manner, a combined door latch and lock indicated in general by the reference numeral 1, this being the usual combined latch and lock which is already installed in a mortise in the door 2 and comprising the usual spindle sleeve 3 having the rectangular opening 4 through

which the ordinary spindle is fitted, the sleeve 3 carrying the usual finger 5 for coaction with the shank 6 of the latch bolt of the mechanism, which bolt is indicated by the numeral 7. While the combined latch 70

and lock which is already installed in the door constitutes no part of the present invention and becomes useless when the present invention is installed, it is illustrated in a 75

general way in Figure 1 and indicated by the numeral 8, so as to more clearly demonstrate the application of the lock unit of the present invention to an ordinary combined latch and lock.

The installed lock likewise embodies the usual face plate 9 which is disposed against the inner face of the door 2, and the numeral 10 indicates the ordinary door knob which is the inner knob and which is mounted upon the inner end of the knob 80

spindle which is indicated by the numeral 11 and which spindle constitutes an element of the unit embodying the invention. The face plate 9 is provided with the usual keyhole 12, and the casing of the latch and lock 85

mechanism is likewise provided with openings 13 through which, in ordinary practice, the lock key is to be inserted as well as through the opening 12, to actuate the locking mechanism. The unit embodying the 90

invention includes, among other elements, a face plate indicated by the numeral 14, and this face plate is disposed against the outer face of the door after removal of the usual outer knob and its spindle. The face plate 95

14 is formed with a vertically extending slot indicated by the numeral 15 and the slot is of such length that when the face plate is applied to the outer face of the door after removal of the outer face plate of the already installed latch and lock some portion of the length of the said slot will be 100

located opposite the keyhole 12 and openings 13. The face plate 14 is secured in place by screws in the usual manner and additionally by a bolt constituting a part of 105

the unit embodying the present invention and indicated in general by the numeral 16. This bolt comprises a shank 17 which is 110

threaded at one end for the application thereto of a nut 18 and this end of the shank is designed to project through the keyhole 12 in the face plate 9. The shank at its 115

opposite end, is formed with a lug 19 extending radially therefrom and of a thickness equal substantially to the diameter of the shank, and outwardly of this lug with an 120

integral head 20 which may be of some ornamental outline and of such vertical dimensions as to completely cover the slot 15 in 125

all positions of adjustment of the bolt 17, depending upon the location of the keyhole 12 and the openings 13. It will be observed 130

by reference to Figures 1 and 2, that the lug 19 engages in the slot 15 so that even should the securing screws for the face plate 14

be removed, the said plate could not be rotated about the spindle 11 in an attempt to disarrange the lock mechanism and open the door.

5 The lock unit embodying the invention includes a hand-knob or other suitable handle member indicated in general by the numeral 21 and this knob, as illustrated in the several figures of the drawings, is in the 10 form of a hollow shell 22 having its outer end closed except for a circular opening 23 which is of a diameter to accommodate the outer end of the key barrel of the lock mechanism, which will presently be described. The shell 22 at its inner end, is fitted rotatably and relatively snugly within a circular recess 24 formed in a boss 25 in turn formed upon the outer face of the face plate 14. An opening 26 is formed in the 15 face plate 14 concentric to the circumferential wall of the recess 24, and lugs 27 project diametrically toward each other from the upper and lower sides of the said opening. These lugs engage in diametric notches 28 formed in the inner end of a bushing 29 which is exteriorly threaded at its said end, as indicated by the numeral 30, a nut 31 being threaded onto this portion of the said bushing and tightened to bear against the inner face of the face plate 14, as clearly 20 shown in Figure 3, for example. The bushing 29 is provided at its outer end exteriorly with a circumferentially extending flange 32 which is of a diameter to more or less snugly 25 fit within the bore of the shell 22 of the knob, and threaded into the inner end of the knob shell is a ring 33 which rotatably fits the body of the bushing and behind which the said flange 32 of the bushing engages, as 30 shown in said Figure 3. In this manner, the inner end of the knob shell is rotatably held within the recess 24, and the shell is likewise 35 in this manner supported for rotation with relation to the said bushing 29.

45 The locking mechanism embodying the present invention includes two cylinders, one indicated in general by the numeral 34 and the other in general by the numeral 35, and a key barrel which is indicated in general 50 by the numeral 36. The cylinders 34 and 35 are fitted into the bore of the shell 22 of the knob 21, the cylinder 34 being located next adjacent the closed outer end of the said shell, and the cylinder 35 being arranged immediately inwardly of the cylinder 34. The cylinder 35 is formed with two oppositely located arcuate slots 37, the portion of the cylinder between the adjacent ends of the said slots constituting abutments 55 indicated by the numeral 38, and the said slots being concentric to the axis of the said cylinder. Bolts 39 are fitted through openings 40 formed in the bushing flange 32 and are fitted into sockets 41 formed in the 60 said cylinder 35. The bolts 39 engage through the slots 37 in the cylinder 35, as clearly shown in Figure 11 of the drawings, and constitute a rigid connection between the bushing 29 and the cylinder 34, so that this cylinder is permanently held against rotation. The cylinder 34 is formed with an opening 42 to which the cylindrical key barrel 36 is rotatably fitted, and the barrel is provided at its outer end with a circumferential flange 43 which abuts against the 70 outer end of the said cylinder 34 and fits snugly and rotatably within the opening 23 in the closed end of the handle 21. The cylinder 35 is likewise formed with a cylindrical opening indicated by the numeral 44, which accommodates the inner end portion of the said spindle and the spindle projects inwardly beyond the inner face of the said cylinder as shown in the several sectional views of the drawings. Washers 45 are fitted onto the end of the key barrel 36, and one of these washers engages the inner face of the cylinder 35. A thimble 46 is fitted onto the end of the said key barrel 36 and a pin 47 is driven diametrically through the said thimble and through the said end of the barrel, thus securing the thimble to the said barrel. The inner end of the thimble is formed with an opening 48, and a link 49 is riveted or otherwise secured as at 50, to the end of the spindle 11, as clearly shown in Figures 3 and 4, for example, of the drawings. The link 49 has a flat portion projecting beyond the end of the spindle and through the opening 48 and into the inner 80 end of the thimble 46, and a lug 51 is stamped or otherwise formed from the wall of the thimble 46 and is engageable by this portion of the said link 49, the said flat portion of the said link, which is indicated by the numeral 52, being somewhat broader than the shank of the link so that when fitted into the thimble with its shank extending through the opening 48, the link will be prevented from being withdrawn from the thimble. The breadth of the said flat portion 52 of the link is substantially equal to the internal diameter of the thimble 46 and it will be understood that the thimble, together with the barrel 36, may have relative rotative movement with respect to the knob spindle 11. The lug 51 constitutes means for engagement against the broadened portion 52 of the link 49 to effect rotation of the spindle 11 to retract the bolt of the latch and lock mechanism when the key barrel 36 is rotated through the medium of a proper key, and on the other hand, the limited movement which the said portion 52 may have in the thimble 46, permits of rotation of the spindle 11, for the purpose stated, through the medium of the inner knob 10, without interference on the part of the said barrel 36.

125 The key barrel 36 is provided with the 130

usual longitudinally extending key slot 52' designed to receive a suitably warded key 53, the wards of which key are designed to shift the tumblers of the two series associated with the cylinders 34 and 35 as will now be described.

The tumblers of one series are indicated in general by the numeral 54, and the tumblers of the other series in general by the 10 numeral 55. Each of the tumblers 54 comprises two sections, one indicated by the numeral 56 and the other by the numeral 57, the sections 56 constituting the locking sections of the tumblers and the sections 57 15 constituting the key-engaged sections of the tumblers. The cylinder 34 is formed with openings 58 in which the sections 56 of the tumblers 54 are slidably mounted and these openings at their outer ends, are closed by 20 a dove-tailed slide 59 which is fitted in a slot formed longitudinally in the outer surface of the said cylinder 34, springs 60 being arranged within the openings and bearing at their outer ends against the said 25 slide and at their inner ends against the outer ends of the tumbler sections 56. The tumbler sections 57 are slidably mounted in radial openings 61 formed in the key barrel 36 and at their outer ends are designed 30 to abut against the inner ends of the sections 56 when the key barrel is rotated to a position with its openings 61 in alinement with the openings 58 in the cylinder 34, the tumbler sections 56 being, at such time, projected into the openings 61, if the key is not 35 inserted into the key slot 52', through the medium of the springs 60.

The other tumblers comprising the series 55 embody, each, two sections, one indicated 40 by the numeral 62 and the other by the numeral 63, and these two sections correspond to the single sections 56 of the tumblers of the series 54. In other words, the combined length of the tumbler sections 62 and 63 45 of each tumbler 55 is equal to the length of the corresponding tumbler section 56 of the tumblers 54. The said tumbler sections 62 and 63 are mounted in openings 64 formed radially in the cylinder 34 and springs 65 50 corresponding to the springs 60 are arranged within these openings and bear at their inner ends against the outer ends of the respective tumbler sections 62 and at their outer ends against a slide 66 which corresponds 55 to the slide 59 heretofore described. The tumbler sections 57 are common to both series of tumblers as will be apparent by reference, for example, to Figures 5 and 8 of the drawings, and it will be observed 60 by reference to these figures that when a suitably warded key is fitted into the key slot of the key barrel 36, the tumbler sections 57 will all register at their outer ends with the circumferential surface of the key 65 barrel, the tumbler sections 56 at such time

likewise registering with the inner ends of the openings 58, and similarly, the tumbler sections 62 will register, at such time, with the said inner ends of the said openings. The manner of functioning of the several 70 tumblers will presently be explained in the description of the operation of the locking mechanism.

The cylinder 35 is formed with a radially extending opening indicated by the numeral 67, and the key barrel 36 is formed with a correspondingly located opening 68 which is in registration with the opening 67, a tumbler pin 69 being slidably mounted in the said openings 67 and 68, as clearly shown, for example, in Figure 5 of the drawings, and having its inner end projecting into the slot 52' for engagement by one of the wards of the key. An opening 70 is formed radially in the wall of the shell 85 22 of the knob 21 and slidably mounted in this opening are tumbler sections 71 and 72, the section 72 being located near the inner end of the opening and the section 71 being located immediately outwardly of 90 and in endwise engagement with the said section 72. The other end of the opening is closed by a plug 73, and a spring 74 is arranged within the opening and bears at one end against the plug 73 and at its other 95 end against the outer end of the said section 71. A similar radial opening 75 is likewise formed in the wall of the shell 22 and slidably arranged therein is a tumbler 76, a spring 77 being arranged within the 100 opening and bearing at one end against the outer end of the said tumbler and at its outer end against a plug 78 which is fitted into and closes the outer end of the said opening 75. It will be observed that the 105 tumbler section 72 and the tumbler 76 are both so located that either may be brought into alinement with the tumbler 69, as will be evident by a comparison of Figures 3 and 8 of the drawings and by reference to 110 Figure 10 of the drawings.

In order that one may determine when the cylinder 35 and the knob 21 are in such position as to provide for insertion of the key to unlock the mechanism, as for example, in the position of the parts illustrated in Figure 3 of the drawings, a small plunger 79 is slidably mounted in an opening 80 formed vertically in the boss 25 at the lower end of the said boss, and the lower 120 end of this opening is closed by a plug 81 and a spring 82 is arranged within the opening and bears at its lower end against the plug and at its upper end against the lower 125 end of the plunger, the said upper end of the plunger being somewhat pointed or tapered as indicated by the numeral 83 and being adapted to project into a shallow socket 84 formed in the outer side of the shell of the knob 21. It will be evident at this point 130

that when the knob is rotated, and it reaches a position of rotation where the socket 84 will be opposite the plunger 79, the rotation of the knob will be somewhat arrested, and the click of the plunger entering the socket will, together, give sensible and audible indication to the user that the knob is in proper position for the insertion of the key.

As heretofore stated, Figures 3 and 4 of the drawings, illustrate the positions occupied by the several component parts of the mechanism when the lock is in locking condition and by reference to these figures and a comparison of the two, it will be observed that at this time, the sections 56 of the tumblers of the series 54 are engaged both in the openings 58 and in the openings 61 so that the key barrel 36 is held fixed with relation to the cylinder 34, and the barrel cannot be turned. Likewise, at this time, the tumbler section 72 will lie within the outer end of the opening 67 in the cylinder 35 with its outer end in registration with the circumferential surface of the cylinder, and the tumbler section 71 will, in a similar manner, have its inner end located flush with the inner surface of the wall of the shell 22 of the knob 21. Under these conditions, therefore, it is impossible to rotate the key barrel 36 and thereby effect rotation of the spindle 11 to retract the lock bolt, and likewise, the knob 21 is unrestrained and freely rotatable so that its rotation cannot by any possibility so connect the parts as to permit of rotation of the spindle 11.

When it is desired to open the door to which the locking mechanism is applied, a suitably warded key, such as the key shown in Figure 5 of the drawings, is inserted into the slot 52' of the key barrel 36 and upon insertion of such a key, the tumblers 54 comprising the sections 56 and 57 will be so shifted as to bring the meeting ends of the respective sections into position flush with the outer surface of the key barrel, and likewise, the tumbler pin 69 will be so shifted as to move the tumbler section 72 into position within the inner end of the opening 70 so that the end of this section 72 and the tumbler 69 will be flush with the outer surface of the cylinder 35. The key may then be rotated toward the right, thus rotating the key barrel and imparting rotary motion to the spindle 11 so as to retract the lock or latch bolt. The key may then be withdrawn, after the key barrel has been rotated to its normal position by the action of the usual spring which constitutes a part of the combination latch and lock originally installed upon the door, said spring, however, not being illustrated as it constitutes no part of the present invention. Upon withdrawal of the key, the parts will resume the position shown in Figure 3 of the drawings.

When the parts are in the position shown in Figure 3, it will be evident the tumbler section 72 will occupy the outer end of the opening 67, so that the opening will be closed and consequently the tumbler 76 cannot be projected into the opening in the rotation of the knob and the knob may be freely rotated without any likelihood of rotating the spindle 11. These same conditions prevail when the key is inserted as shown in Figures 5 and 6.

It is, of course, desirable that the mechanism be capable of adjustment so that the spindle 11 may be actuated through rotation of the hand knob 21, inasmuch as the unit intended for employment in office buildings, stores and various establishments where it is desired to lock the doors after business hours but, at the same time, admit of ready entrance and exit by way of the doors during business hours. This may be accomplished by inserting the key into the barrel, when the parts are in the position shown in Figure 3, and then rotating the barrel, through the medium of the key, toward the left, to bring the opening 67 opposite the opening 75, and then retracting the key so as to permit the tumbler 76 to enter the outer end of the said opening 67, as shown in Figure 8 of the drawings. This serves to connect the knob with the cylinder 35 and, inasmuch as the cylinder is in turn, connected with the key barrel, rotative movement of the knob will effect rotation of the spindle 11. In rotating the knob, its movement will be limited by the engagement of the abutment portion 38 of the cylinder 35, with the bolt 39. In order to readjust the mechanism so that it will lock the door, it is only necessary to reinsert the key, with the parts in the position shown in Figures 7 and 8 of the drawings, which will effect adjustment of the tumbler sections 56 and 57 to the position shown in Figure 5, and adjustment of the tumbler 69 to such position that the inner end of the tumbler 76 will be located flush with the inner surface of the knob shell 22, and then rotate the key barrel and the parts associated therewith to the right until the opening 70 is in registration at its inner end with the outer end of the opening 67 as shown in Figure 5, whereupon the key may be withdrawn and the parts will assume the locking position shown in Figures 3 and 4.

Having thus described the invention, what I claim is:

1. A lock unit applicable to the latch mechanism of an installed combination door latch and lock, comprising a spindle constituting a substitute for the spindle of the latch mechanism, a fixed tumbler cylinder with relation to which the spindle is rotatable, a key barrel rotatable in the cylinder and operatively connected with the said spindle, a cylinder rotatable with the spin-

- dle, a knob rotatable upon the first mentioned cylinder, and key controlled means operable to lock the key barrel with the first mentioned cylinder and permit rotation of the knob and also operable to disconnect the key barrel from the said cylinder and lock the knob and second mentioned cylinder for rotation in unison. 5
2. A lock unit applicable to the latch mechanism of an installed combination door latch and lock, comprising a spindle constituting a substitute for the spindle of the latch mechanism, a fixed tumbler cylinder with relation to which the spindle is rotatable, a key barrel rotatable in the cylinder, operative connection between the key barrel and the said spindle connecting the spindle with the barrel for rotation therewith in one direction of rotation of the said barrel and permitting limited rotation of the spindle independently of the barrel, a cylinder rotatable with the spindle, a knob rotatable upon the first mentioned cylinder, and key controlled means operable to lock the barrel with the said first mentioned cylinder and permit the rotation of the knob, and also operable to disconnect the key barrel from said cylinder and lock the knob and second mentioned cylinder for rotation in unison. 10
3. A lock unit applicable to the latch mechanism of an installed combination door latch and lock, comprising a spindle constituting a substitute for the spindle of the latch mechanism, a fixed tumbler cylinder with relation to which the spindle is rotatable, a key barrel rotatable in the cylinder and operatively connected with the said spindle, tumblers associated with the said barrel and the said cylinder and key-shiftable to prevent and permit rotation of the key barrel with relation to the cylinder, a cylinder rotatable with the spindle, a tumbler associated with the second mentioned cylinder, and a knob rotatable upon the first mentioned cylinder, the tumbler of the second mentioned cylinder coacting with the knob to connect the knob with the said second cylinder and also disconnect the same therefrom. 15
4. A lock unit applicable to the latch mechanism of an installed combination door latch and lock, comprising a spindle constituting a substitute for the spindle of the latch mechanism, a fixed tumbler cylinder with relation to which the spindle is rotatable, a key barrel rotatable in the cylinder and operatively connected with the said spindle, a key-actuated tumbler associated with the said barrel and said cylinder and normally assuming a position locking the key barrel with the cylinder and adjustable through the insertion of a proper key into the barrel to permit of rotation of the key barrel with relation to the said cylinder, a second cylinder rotatable with the key bar- 20
- rel, a knob freely rotatable upon the first mentioned cylinder and enclosing the same and the second mentioned cylinder and the key barrel, and a tumbler associated with the said knob and with the second mentioned cylinder and adjustable through the insertion of a proper key into the said barrel, to permit of free rotation of the key barrel independent of the knob and likewise provide for rotation of the key barrel with the said knob. 25
5. A lock unit applicable to the latch mechanism of an installed combination door latch and lock, comprising a spindle constituting a substitute for the spindle of the latch mechanism, a fixed tumbler cylinder with relation to which the spindle is rotatable, a key barrel rotatable in the cylinder and operatively connected with the said spindle, a second cylinder rotatable with the said key barrel, a knob freely rotatable with relation to the first mentioned barrel, the said knob enclosing the said cylinders and the barrel, and key-actuated tumbler means for selectively connecting the knob and said second mentioned cylinder; locking the barrel with the first mentioned cylinder and freeing the knob from the second mentioned cylinder; and, freeing the key barrel from the said first mentioned cylinder. 30
6. A lock unit applicable to the latch mechanism of an installed combination door latch and lock, comprising a spindle constituting a substitute for the spindle of the latch mechanism, a supporting plate for attachment to the door in which the said combination door latch and lock is installed, a bushing fixed with relation to the said supporting plate and having an opening to accommodate the said spindle, a tumbler barrel supported by the said bushing in spaced relation thereto and thus held in a relatively fixed position, a knob freely rotatable upon and with relation to the said bushing and the said cylinder, a key barrel rotatably mounted in the said cylinder, a cylinder rotatable with the key barrel and housed within the knob beside the first mentioned cylinder, operative connection between the key barrel and said spindle, and key-actuated tumbler means for selectively connecting the knob and second mentioned cylinder; locking the key barrel with the first mentioned cylinder and freeing the knob from the second mentioned cylinder; and, freeing the key barrel from said first mentioned cylinder. 35
7. A lock unit applicable to the latch mechanism of an installed combination door latch and lock, comprising a spindle constituting a substitute for the spindle of the latch mechanism, a supporting plate for attachment to the door in which the said combination door latch and lock is installed, a bushing fixed with relation to the said sup- 40

porting plate and having an opening to accommodate the said spindle, a tumbler barrel supported by the said bushing in spaced relation thereto and thus held in a relatively 5 fixed position, a knob freely rotatable upon and with relation to the said bushing and the said cylinder, a key barrel rotatably mounted in the said cylinder, a cylinder rotatable with the key barrel and housed within the knob beside the first mentioned cylinder, operative connection between the key barrel and said spindle, and key-actuated tumbler means for selectively connecting the 10 knob and second mentioned cylinder; locking the key barrel with the first mentioned cylinder and freeing the knob from the second mentioned cylinder; and, freeing the key barrel from said first mentioned cylinder, the said tumbler means including a 15 tumbler associated with the second mentioned cylinder and extending through the key barrel into the key slot therein, tumbler seats in the knob at spaced points in the circumference thereof in circumferential alinement with the said tumbler of the second 20 mentioned cylinder, a one-piece tumbler in one of said seats adapted to enter the seat for the first mentioned tumbler to lock the knob and second mentioned cylinder for rotation in unison, and a tumbler in the other seat in the knob comprising sections proportioned, in all positions of adjustment of the 25 first mentioned tumbler, to permit of rotation of the knob with relation to the said 30 second mentioned tumbler.

8. A lock unit applicable to the latch mechanism of an installed combination door latch and lock, comprising a spindle constituting a substitute for the spindle of the latch 35 mechanism, a supporting plate for attachment to the door in which the said combination door latch and lock is installed, a bushing fixed with relation to the said supporting plate and having an opening to accommodate the said spindle, a tumbler barrel supported by the said bushing in spaced 40 relation thereto and thus held in a relatively fixed position, a knob freely rotatable upon and with relation to the said bushing and the said cylinder, a key barrel rotatably mounted in the said cylinder, a cylinder 45 rotatable with the key barrel and housed within the knob beside the first mentioned cylinder, operative connection between the key barrel and said spindle, and key-actuated tumbler means for selectively connecting the 50 knob and second mentioned cylinder; locking the key barrel with the first mentioned cylinder and freeing the knob from the second mentioned cylinder; and, freeing the key barrel from said first mentioned cylinder, the said tumbler means including a 55 tumbler comprising sections associated with the key barrel and first mentioned cylinder and normally locking the key barrel with relation to the first mentioned cylinder and 60 key-shiftable to position to permit of rotation of the said key barrel with relation to the said first mentioned cylinder, and further comprising a tumbler associated with the second mentioned cylinder and extending through the key barrel into the key slot therein, tumbler seats in the knob at spaced 65 points in the circumference thereof in circumferential alinement with the said tumbler of the second mentioned cylinder, a one-piece tumbler in one of said seats adapted to enter the seat for the first mentioned tumbler to lock the knob and second mentioned cylinder for rotation in unison, and a tumbler in the other seat in the knob comprising sections proportioned, in all positions of 70 adjustment of the first mentioned tumbler, to permit of rotation of the knob with relation to the said second mentioned tumbler.

relation to the first mentioned cylinder and key-shiftable to position to permit of rotation of the said key barrel with relation to the said first mentioned cylinder.

9. A lock unit applicable to the latch mechanism of an installed combination door latch and lock, comprising a spindle constituting a substitute for the spindle of the latch mechanism, a supporting plate for attachment to the door in which the said combination door latch and lock is installed, a bushing fixed with relation to the said supporting plate and having an opening to accommodate the said spindle, a tumbler barrel supported by the said bushing in spaced 70 relation thereto and thus held in a relatively fixed position, a knob freely rotatable upon and with relation to the said bushing and the said cylinder, a key barrel rotatably mounted in the said cylinder, a cylinder rotatable with the key barrel and housed within the knob beside the first mentioned cylinder, operative connection between the key barrel and said spindle, and key-actuated tumbler means for selectively connecting the 75 knob and second mentioned cylinder; locking the key barrel with the first mentioned cylinder and freeing the knob from the second mentioned cylinder; and, freeing the key barrel from said first mentioned cylinder, the said tumbler means including a tumbler comprising sections associated with the key barrel and first mentioned cylinder and normally locking the key barrel with relation to the first mentioned cylinder and 80 key-shiftable to position to permit of rotation of the said key barrel with relation to the said first mentioned cylinder, and further comprising a tumbler associated with the second mentioned cylinder and extending through the key barrel into the key slot therein, tumbler seats in the knob at spaced 85 points in the circumference thereof in circumferential alinement with the said tumbler of the second mentioned cylinder, a one-piece tumbler in one of said seats adapted to enter the seat for the first mentioned tumbler to lock the knob and second mentioned cylinder for rotation in unison, and a tumbler in the other seat in the knob comprising sections proportioned, in all positions of 90 adjustment of the first mentioned tumbler, to permit of rotation of the knob with relation to the said second mentioned tumbler.

key barrel with relation to the cylinder, a cylinder rotatable with the spindle, a tumbler associated with the second mentioned cylinder, a knob rotatable upon the first mentioned cylinder, the tumbler of the second mentioned cylinder coacting with the knob to connect the knob with the said sec-
ond cylinder and also disconnect the same therefrom, and means for indicating when the knob is in position for insertion of the ¹⁰ key to properly actuate the lock mechanism.

In testimony whereof I affix my signature.

HERMAN H. CLAUSSEN. [L.S.]
